UNITED STATES PATENT OFFICE.

CHARLES A. RICH, OF PROVIDENCE, RHODE ISLAND, ASSIGNOR TO BROWN & SHARPE MANUFACTURING COMPANY, OF PROVIDENCE, RHODE ISLAND, A CORPORATION OF RHODE ISLAND.

SCREW-MACHINE.

1,131,274.

Specification of Letters Patent. Patented Mar. 9, 1915.

Application filed September 2, 1911. Serial No. 647,307.

To all whom it may concern:

Be it known that I, CHARLES A. RICH, of the city and county of Providence and State of Rhode Island, have invented certain new and useful Improvements in Screw-Machines; and I do hereby declare the following specification, taken in connection with the accompanying drawings, forming a part of the same, to be a full, clear, and exact description thereof.

The present invention relates to screw machines, and more especially to that class of screw machines in which a rod of stock is intermittently fed forward for the prescribed distance to form an article and is held by the jaws of a revolving chuck and successively acted upon by a series of tools carried by an indexing turret-head. In certain machines of this class the series of tools are secured in a turret-head mounted on a turret-slide, and the reciprocating feed and return movements are imparted to said turret-slide, which thus constitutes a feed-slide. In such machines both the turret-slide and the turret-head mounted thereon, together with all of the tools secured in said turret-head, are reciprocated back and forth in connection with the operation of each successive tool upon the work. A machine of this type is shown in the patent to Davenport, No. 604,306, dated May 17, 1898. In certain other machines the several tools are carried by a series of tool-carriers which are mounted for separate and individual reciprocation in a turret-head which is mounted in stationary bearings, each tool-carrier being in turn connected with a reciprocating feed-slide. In such machines only the feed-slide with one of the tool-carriers connected therewith requires to be reciprocated for the feed and return movements, each tool-carrier being separately reciprocated, and only one of said carriers being reciprocated in connection with each successive operation. A machine of this type is shown in the patent to Gabriel, No. 786,353, dated April 4, 1905.

Certain features of the present invention are applicable to, and may be employed in connection with, both types of machines above referred to.

The machine shown in the accompanying drawings is especially designed as a high speed machine, and to that end the machine is of that type in which a series of individually reciprocating tool-spindles are em-

ployed, as machines of that type can be run at a much higher speed than machines in which a heavy turret-slide and the attached parts are required to be reciprocated in connection with the operation of each successive tool.

Certain further features of the invention therefore are more particularly applicable to, and adapted to be employed in connection with, machines embodying a series of individually reciprocating tool-carriers, and in which the turret has simply a rotary movement imparted thereto for the purpose of indexing the same.

In both types of machines above referred to it is customary to employ separate and independent mechanisms for imparting feed and return movements to the reciprocating feed-slide, one of these mechanisms serving to impart to said slide a slow feeding movement, and the other mechanism serving to impart to said slide a quick return movement. In certain cases, as for example in the Davenport and Gabriel patents herein-before referred to, the quick return mechanism is so constructed that it will also serve to move the tool or tools approximately up to the work at the same high rate of speed, leaving the slow running mechanism to operate only to effect the feed during the actual operation of the tools.

The primary object of the present invention is to provide a machine which may be run at a high speed, and in which the quick return movement of the tool-carrier will be effected at a materially higher speed than has been heretofore possible or practicable in machines of this class.

To that end the invention consists primarily in the employment, in combination with the main slide,—the turret slide in the one case or the feed-slide for individual tool-spindles in the other,—of an auxiliary or supplemental slide, and means whereby the quick return movements will be imparted only to such auxiliary or supplemental slide, thereby avoiding the necessity of imparting high speed movements to the heavy, or comparatively heavy, main slide, which is objectionable.

The invention further consists in the combination, with a series of individually movable tool-carriers, of a main slide, an auxiliary slide adapted to be connected with each of said individual tool-carriers suc-

sively, means for imparting quick return movements to said auxiliary slide, and a fixed stop for arresting the return or rearward movement of said auxiliary slide.

5 When the operating tool consists of a threading die it is usually necessary that there shall be a rearward movement of the feed-slide during the unthreading of the die. Such rearward movement cannot be effected by the quick return mechanism, but must be effected or controlled by the feed-cam. In such case therefore the quick return mechanism must not begin to operate until after the die has cleared the work. At this time, 15 however, a certain amount of return movement will already have been imparted to the feed-slide under the action or control of the feed-cam. Consequently when a fixed stop is employed for arresting the rearward 20 movement of the feed-slide, the distance through which the feed-slide is to be moved by the quick return mechanism is correspondingly lessened.

A further feature of invention therefore 25 consists in means for automatically breaking the connection between the quick return mechanism and the feed-slide, whereby the rearward movement of said feed-slide may be arrested before the return mechanism 30 has completed its operative movement, and whereby said return mechanism may continue its operative movement after the rearward movement of the feed-slide has been arrested.

35 The invention further consists in means whereby the feed-slide may be disconnected from the quick return mechanism in connection with setting up the machine, for example, and may be automatically connected 40 with said quick return mechanism when the machine is again started.

45 The invention further consists in the combination with a main slide and an auxiliary slide, of a feed-cam therefor, a spring for imparting return movements to said auxiliary slide, and means for controlling the operation of said spring.

50 The invention further consists in the combination with a main slide and an auxiliary slide, of a feed-cam therefor, a spring for imparting return movements to said auxiliary slide, and means mounted on said main slide for controlling the operation of said spring.

55 The invention further consists in the combination with a main slide and an auxiliary slide, of a feed-cam therefor, a spring for imparting return movements to said auxiliary slide, means for controlling the operation of said spring, and means for positively returning said auxiliary slide in case said spring fails to return the same.

60 The invention further consists in the combination, with a main slide and an auxiliary slide, of a feed-cam therefor, a tool-turret,

means for indexing said tool-turret, and means for returning said auxiliary slide to its rearward position before the indexing movement of said tool-turret commences.

In the accompanying drawings, in which the features of invention are shown as embodied in a screw machine of that type in which the several tool-spindles are mounted for separate and individual reciprocation, Figure 1 is a front elevation of such machine. Fig. 2 is a rear elevation. Fig. 3 is an elevation of the right hand end of the machine partly in section and with certain of the parts omitted or broken away. Fig. 4 is a plan view of the turret mechanism. Fig. 5 is a front elevation of the return mechanism for the tool-spindles showing the parts in the position which they occupy when the auxiliary slide has been moved backward by hand. Fig. 6 is a section on the line $x-x$ of Fig. 1. Fig. 7 is a partial horizontal sectional view with the front and back shafts removed. Fig. 8 is a front elevation on an enlarged scale of the feed and return mechanisms for the tool-spindles, 90 showing one of the tool-spindles in its forward position. Fig. 9 is a corresponding front elevation of the feed and return mechanisms showing one of the tool-spindles in its rearward position, and with 95 the parts in the position they occupy at the beginning of the indexing of the turret. Fig. 10 is a corresponding front elevation of the feed and return mechanisms, showing the parts in the position which they occupy 100 at the end of the indexing operation and showing the next tool-spindle in series in its rearward position and ready to be fed forward. Figs. 11, 12 and 13 are detail views.

The machine shown in the drawings is a 105 single spindle machine, that is, has a single work-spindle. The work-spindle end of the machine is or may be substantially like the machine shown in the patent to Davenport, No. 604,306, above referred to, and this part 110 of the machine need be only generally described.

The work-spindle 1 is adapted to be rotated in opposite directions by the two oppositely running pulleys 2 and 3 loosely 115 mounted on said spindle and adapted to be alternately connected to the spindle in the usual manner by means of a clutch (not shown). 4 is the clutch-lever for opening and closing the jaws of the chuck carried by the work-spindle, said lever being operated by a cam 5 on the cam-shaft 6. 7 is the feed-lever for operating the feed-tube for feeding forward the rod of stock, said lever being operated by a cam 8 on said cam-shaft. 120 Preferably means are provided for adjusting the length of the feed, such means being shown in Fig. 2, and being the same as that shown and described in the Davenport patent referred to. 125

9 is the main driving shaft of the machine from which the cam-shaft and all the other parts of the machine, except the work-spindle and the tool-spindles, are operated. 5 The driving pulley 10, instead of being mounted directly on the shaft 9, is preferably mounted on a short shaft 11 which is adapted to be connected to and disconnected from the driving shaft 9 by means of a clutch 12. By the shifting of said clutch 10 the operation of all those parts of the machine which are operated from the shaft 9 may be started or stopped.

Mounted on the shaft 9 is a sleeve 13 provided with a cam 14 adapted to actuate the clutch-lever 15, the movement of which in one direction or the other serves to connect one or the other of the pulleys 2 and 3 with the work-spindle. In the construction 20 shown in the drawings the cam 14 is a single acting cam and actuates the lever 15 to shift the clutch in one direction, said lever being operated to shift the clutch in the opposite direction by means of a spring-plunger 16 controlled as to its action by a transversely 25 arranged lever 16^a. The cam-sleeve 13 is adapted to be connected to and disconnected from the shaft 9 by means of a clutch 17, the position of which is controlled by a transversely 30 arranged lever 18.

As will be understood, the cam-shaft 6 is to be revolved a single revolution at the proper time to open and close the chuck-jaws and to feed forward a new length of stock. For this purpose there is loosely 35 mounted on the shaft 9 a two-part sleeve, the two parts of said sleeve being rotatably but slidably connected together. The sliding member 19 of said sleeve is provided 40 with a clutch-face 20 adapted to engage a corresponding clutch-face on a collar 21 secured to said shaft 9. The other member 22 of said sleeve, shown in dotted lines in Fig. 2, is provided with a gear 23 which 45 meshes with a gear (not shown) on the cam-shaft 6. The member 19 of the sleeve referred to is acted upon by a spring (not shown), and the movement of said member to engage and disengage the clutch-face 20 50 is controlled by a transversely arranged lever 24.

Referring now to the tool-spindle end of the machine, to which the present features of invention chiefly relate, a series of separate and individually sliding tool-spindles 25 are mounted in a turret-head which comprises two disks 26 and 27 mounted to revolve in housings 28 and 29 and secured to a short shaft 30. Mounted to slide in ways 55 on the frame of the machine is a slide 31, which may be termed the main feed-slide. Mounted to slide in ways formed on said main slide is another slide 32, which may be termed the auxiliary feed-slide. Each of 60 the tool-spindles 25 is adapted, when the

turret is indexed, to be in turn engaged with said auxiliary feed-slide. For this purpose each of the tool-spindles has clamped thereon a split collar 33 provided with a groove 34, while the auxiliary feed-slide is 70 provided with a segmental rib 35 adapted to engage successively the grooves 34 in the split collars 33. The tool-spindles 25 are held from rotation in the turret-head by means of a series of keys 36 secured in the 75 shaft 30 which engage grooves formed in the split collars 33. Formed on the inner surface of a segmental guide-ring 37 is a rib 38 adapted to engage the grooves 34 in the split collars, said rib serving to hold 80 the inactive tool-spindles in their retracted position and to guide said spindles during the indexing of the turret.

Referring now to the means for indexing the turret-head, there is loosely mounted on the shaft 9 on the opposite side of the collar 21 another two-part sleeve, the two parts of which are rotatably but slidably connected together. The sliding member 39 of said sleeve is provided with a 90 clutch face 40 adapted to engage a corresponding clutch-face on that side of the collar 21. Said sliding member 39 is acted upon by a spring (not shown) and the movement of said member is controlled by a 95 transversely arranged lever 41. The other member 42 of said sleeve is provided with a gear 43, which meshes with a gear 44 secured to the shaft 45 mounted in bearings in the frame. Secured to the shaft 45 is a 100 crank-disk 46 carrying a crank-pin 47 preferably provided with an anti-friction roll. Said crank-pin 47 is adapted to engage radial slots 48 formed in a disk 49 secured to a shaft 50 mounted in bearings in the 105 frame. Secured to the disk 49 is a gear 51 which meshes with a gear 52 secured to or formed on one of the disks of the turret-head. As will be understood, the rotation of the crank-disk 46 serves, by the engagement of the crank-pin 47 with one of the radial slots 48 in the disk 49 to give a partial rotation to said disk and thus to the 110 turret-head. It will also be understood that the slots 48 in the disk 49 are so arranged 115 that the crank-pin will enter and leave said slots while moving radially of the disk 49, and that thus the turret will be gradually started and stopped and may be indexed quickly without any jar, either in starting 120 or stopping. Preferably a locking pin (not shown) will be employed for locking the turret in indexed position at the end of each indexing operation.

Referring next to the means for imparting feed and return movements to the individual tool-spindles, the same embodies a slow running feed-cam for advancing or feeding the tool-spindle during the operation of cutting, and another and quick act- 125 130

ing mechanism for returning the tool-spindle, said quick acting mechanism also preferably serving to advance the tool-spindle to bring the tool up to the work. With such 5 construction the tool-spindle is returned, the turret indexed, and the succeeding tool-spindle advanced to bring the next tool up to the work while the roll is passing over the high point of the feed-cam and passing low 10 enough to bring it into proper position to feed forward said last mentioned tool-spindle during the cutting operation.

Referring first to the means for rotating the slow running feed-cam and for feeding 15 forward such individual tool-spindles in cutting, the shaft 9 is provided at its left hand end, Fig. 2, with the gear 53 which meshes with an intermediate gear 54 loosely mounted on a stud, which intermediate gear 20 meshes with a gear 55 secured to a shaft 56. The gears 53, 54, and 55 are preferably change gears. The shaft 56 is provided with a worm 57 which engages with a worm-wheel 58 secured to one end of a 25 transverse shaft 59. Secured to the shaft 59 is a gear 60 (see Fig. 7) which meshes with a gear 61 secured to a parallel transverse shaft 62, on which last mentioned shaft is secured the slow running feed-cam 30 63. Said cam 63 is removable and, as will be understood, cams of varying shapes and with a varying number of lobes are to be employed, according to the character of the article to be produced and the number of 35 tool-spindles to be used in the production of such article. In the drawings six tool-spindles are shown, and assuming that all of these spindles are to be employed in the production of a given article, the cam 63 will 40 be provided with a corresponding number of lobes, two only of which are for convenience shown in the drawings designated as 63^a and 63^b, respectively. Mounted in suitable bearings in the frame is a rock- 45 shaft 64 provided with arms 65 and 66. The arm 65 is preferably provided with an anti-friction roll 67 arranged to ride upon the periphery of the feed-cam 63. The arm or lever 66 is provided at its upper end with a gear-segment 68 which meshes with a rack 50 69 secured to the main feed-slide 31.

Referring next to the quick acting mechanism for returning and subsequently advancing each individual tool-spindle, the 55 shaft 45 is provided with an elongated gear 70 which meshes with a gear 71 mounted to revolve on a stud 72 secured on the main feed slide. Secured to the gear 71 is a bevel gear 73 which meshes with a bevel gear 74 60 secured to a shaft 75. Secured to the shaft 75 is a crank-disk 76 carrying a crank pin 77. Said crank-disk 76, which, as will be seen, is mounted on the main feed-slide, is connected to the auxiliary feed-slide 32 by 65 a connection which embodies a two-part

telescopic connecting rod 78, 79. One end of the part 78 of said connecting rod is pivotally connected to the crank-pin 77, while one end of the other part 79 of said connecting rod is pivotally connected to the 76 auxiliary slide in the following manner: Mounted to slide in the main feed-slide 31 is a block 80. Projecting from one side of said block is a pin 81 upon which the enlarged end of the part 79 of the two-part 78 connecting rod is pivotally mounted. The auxiliary feed-slide 32 is provided with a downwardly extending bracket 82 in which is slidably mounted a spring-pressed pin 83, said pin being acted upon by a spring 84 surrounding the same. Said spring 84 bears at one end against a shoulder 85 formed on the pin and at the other end against a plug 86 screwed into or otherwise secured to the bracket 82. The pin or projection 81 on the block 80 is provided with a hole adapted to receive the inner end of the pin 83. When the end of the pin 83 is, by the action of the spring 84 projected into the hole in the pin 81 the auxiliary feed-slide 32 and the block 80 are thereby connected together and said auxiliary feed-slide is thus connected through the two-part connecting rod with the crank-disk 76 and with the main feed-slide. When the pin 83 is withdrawn from 95 engagement with the pin or projection 81 on the block 80 the auxiliary feed-slide 32 may be moved backward and returned to its normal position by hand and independent of the block 80, which remains connected through the two-part connecting rod with the crank-disk. The pin 81 is cut away to 100 form an annular shoulder 81^a for a purpose to be hereinafter described.

The two parts 78 and 79 of the two-part 105 connecting rod are normally connected or latched together by a latch in the form of a hook-lever 87 pivoted on the part 79, the hook of which lever is adapted to enter a notch 88 formed in the part 78 and to engage 110 the wall of said notch, as shown in Fig. 8. A spring 89 is arranged to bear against the tail of said hook-lever 87, said spring acting to normally hold said lever or latch in engaging position and thus to connect the two 115 parts 78 and 79 of the connecting rod. The purpose in making the connecting rod 78, 79 in two parts normally connected together is in order that by disconnecting the two parts of said connecting rod the auxiliary 120 feed-slide may be disconnected from the main feed-slide, and so that as the result of such disconnection the return movement of the auxiliary feed-slide may be arrested before the quick return mechanism carried by 125 the main feed-slide has completed its operative movement. Secured to the frame is a cam 90 located in the path of a projection 91 on the hook-lever 87 when said hook-lever is in the position which it occupies 130

when the two parts of the connecting rod are latched together as shown in Fig. 8. With the parts in this position, when the auxiliary feed-slide is moved back by the quick return mechanism, as hereinafter described, the projection 91 on the hook-lever 87 is thereby brought into engagement with the cam 90, which said cam, as the auxiliary feed-slide continues to move backward, acts to turn the hook-lever about its pivot, thereby with drawing the hook-end of said lever from the notch 88, thus disconnecting the two parts of the connecting rod and consequently disconnecting the auxiliary feed-slide from the main feed-slide. Preferably the two parts of the connecting rod are unlatched and disconnected shortly before the auxiliary feed-slide has reached its rear-most position, and so that the final rearward movement of said auxiliary feed-slide is effected by the action of the spring 92 entirely independent of the rotation of the crank-disk 76, said spring 92 serving, as will be more fully pointed out later, to move said auxiliary slide into engagement with a fixed abutment 32^a and to hold said auxiliary slide against such fixed abutment during the operation of indexing. Preferably the arm or segment-lever 66 is provided with a projection 66^a adapted to engage the fixed frame, as shown in Fig. 8 for a purpose to be hereafter referred to.

The spring 92 acts in effect upon the auxiliary feed-slide in the following manner: Said spring 92 is located partly in a hole formed in the frame of the machine and partly in a hole formed in the block 80, one end of said spring abutting against the bottom of the hole in the frame, and the other end abutting against the bottom of the hole in said block. As said block 80 is, as above described, normally connected with the auxiliary feed-slide, said spring 92 thus acts in effect upon said auxiliary feed-slide. Preferably a second spring is employed which is adapted to act upon the main feed-slide. A spring-pressed pin or plunger 93 acted upon by a spring 94 is mounted in the frame and arranged to bear against the arm or segment-lever 66 and thus through said segment-lever is adapted to act upon the main feed-slide. As heretofore explained, the operation of the spring-plunger 16 and of the three several clutch members 17, 20, and 41 is controlled each by a transversely arranged lever, viz., the levers 16^a, 18, 24, and 41. The actuation of each of these four levers is controlled by tappets adjustably mounted on disks secured to the front shaft of the machine, all as more fully explained in the Davenport patent above referred to.

For the purpose of facilitating the removal and replacement of the cams 95 and 96, which operate the cross-slides of the ma-

chine, the front shaft referred to is preferably made in two parts 97 and 98, the two parts being normally connected by a coupling 99 and so that the part 98 will be rotated by the part 97. Secured to the shaft 70 59 is a bevel-gear 100 which meshes with a bevel-gear 101 on the part 97 of the front shaft, and so that said front shaft is thereby rotated from the main driving shaft 9 through the train of gearing leading therefrom to said shaft 59, as above described. Secured to the part 97 of the front shaft are two disks 102 and 103, the disk 102 being provided with tappets 104 for actuating the lever 41 and the disk 103 being provided 80 with tappets 105 for actuating the lever 24. Secured to the part 98 of the front shaft is another disk 106, provided on one side with tappets 107 for actuating the lever 18 and provided on the opposite side with tappets 85 108 for actuating the lever 16^a. In the case of some of the tools to be employed in a machine of this character it is desirable that the tool shall be rotated, as for example in the case of a screw-cutting die or in the case 90 of a drill. Means are therefore provided for rotating one or more of the tools. In the construction illustrated means are shown for rotating only one of the tools, but means may, if desired, be provided for rotating one 95 or more additional tools. Each of the tool-spindles 25 is hollow, and when provision is to be made for rotating a tool a rotary spindle is located within one of the hollow tool-spindles 25. Said rotary spindle is provided 100 at its forward end with a tool-holder 109 (see Fig. 1) and is provided at its rear end with a gear 110 which meshes with an elongated gear 111 rotatably connected with the pulley 112. Both the gear 111 and the pulley 112 may be loosely mounted upon a stud 113 secured in a bracket 114 attached to the frame. If desired, however, only the pulley 112 may be mounted on this stud and the elongated gear 111 may be loosely mounted upon 110 a prolongation of the shaft 30 of the turret-head. If desired the direction of rotation of the rotary spindle may be changed by employing an intermediate gear adapted to be engaged by the gear 111 and in turn engaging the gear 110.

The operation of the machine above described, generally considered, that is, in the respect that a rod of stock is intermittently fed forward and is acted upon successively 120 by a series of tools carried in a turret-head, said turret-head being intermittently indexed, is similar to that of other machines of this character and need not therefore be described in detail. So also the operations 125 performed at the work-spindle end of the machine are performed in substantially the same manner as in the machine of the Davenport patent above referred to and likewise need not be herein particularly de- 130

scribed. It may, however, be stated that with the clutch-lever in the position shown in Fig. 2 the clutch is in engagement with the reverse pulley 3, and that at the proper time the clutch member 17 will be tripped and released by the action of one of the tappets 107 on the lever 18, thereby causing the cam 14 to be rotated and act upon the clutch-lever 15 to shift the clutch into engagement with the forwardly rotating pulley 2. It will also be understood that at the desired time the spring-plunger 16 will be tripped by the action of one of the tappets 108 on the lever 16^a, whereupon said spring-plunger will act upon the clutch-lever 15 to shift the clutch into engagement with the reverse pulley 3. It will also be understood that when the rod of stock is to be fed forward the clutch member 20 will be tripped and released by the action of one of the tappets 105 on the lever 24, thereby causing the cam-shaft 6 to be rotated and by the rotation of the cams 5 and 8 causing the jaws of the chuck to be opened, the rod feeding devices to be operated and the chuck-jaws to be again closed upon the rod.

Understanding that a rod of stock is held in and rotated by the work-spindle, and that such rod of stock is intermittently fed forward the desired distance for each article to be formed therefrom, the operation of that part of the machine which has to do with feeding forward and retracting the tools and with indexing the turret-head, whereby said tools are caused to act successively upon the rod of stock, is as follows: As will be understood, with the construction shown and described, the several tools are advanced and retracted separately and individually, only the one tool which at the time is to act upon the rod of stock being thus advanced and retracted, while all of the other tools remain in their retracted position. Assuming now that the turret-head has been indexed and that one of the tool-spindles 25 has been advanced by the quick acting mechanism up to the work, said tool-spindle is then fed forward by the action of one of the lobes of the slow running feed-cam, for example, the lobe 63^a, to cause the tool carried thereby to operate upon the work. This serves to bring the parts into the position shown in Fig. 8, wherein the tool-spindle 25 therein shown is in its extreme forward position. At this time and with the parts in this position the clutch member 39 is tripped and released by the action of one of the tappets 104 on the lever 41, thereby causing the gears 43 and 44 and the shaft 45 to be rotated. The rotation of the shaft 45 serves to rotate the crank-disk 46 which operates the indexing mechanism, and also serves through the connecting gearing to rotate the crank-disk 76, by means of which

quick return and advancing movements are imparted to the auxiliary feed-slide.

In the present machine in which the several tools are carried by tool-spindles which are individually advanced and retracted, and in which the turret-head itself has no longitudinal movement, it is desirable that when indexing takes place the auxiliary feed-slide, with which each of the tool-spindles is successively connected, shall remain stationary during the indexing operation, and it is preferred that at this time said auxiliary feed-slide shall be in its rearmost position. To this end the auxiliary feed-slide and the tool-spindle at the time connected therewith are retracted by the quick return mechanism to their rearmost position, the turret-head is then indexed to bring the next tool-spindle into operative position and to connect the same with the auxiliary feed-slide, and then said slide is advanced by the quick-acting mechanism to bring the tool in said spindle up to the work ready for said tool to be fed forward by the action of the feed-cam. While, therefore, the operation of indexing does not take place until after the auxiliary feed-slide has been retracted, it will be convenient to first describe the operation of the indexing mechanism, and then to describe the operation of the quick-acting mechanism in retracting and advancing the auxiliary feed-slide. When the shaft 45 begins to rotate, the crank-pin 47 is in the position shown in Fig. 3. As the crank-disk 46 is rotated, the crank-pin 47 is caused to enter one of the slots 48 in the disk 49, and so that the continued rotation of said crank-disk will cause the disk 49 to be rotated and thus, through the gears 51 and 52, cause the turret-head to be indexed. The indexing movement of the turret-head will cause the block 33 on the tool-spindle 25 to be carried out of engagement with the rib 35 on the auxiliary feed-slide and cause the corresponding block on the next tool-spindle to be brought into engagement with said rib, thereby connecting said last mentioned tool-spindle with the auxiliary feed-slide ready to be advanced thereby. It will be understood that during this indexing operation the auxiliary feed-slide will be held in its rearward position against the abutment 32^a by the action of the spring 92 on said slide. The rotation of the shaft 45, as above stated, also serves to rotate the crank-disk 76. Assuming the parts to be in the position shown in Fig. 8, that is, with the auxiliary feed-slide in its extreme forward position and the tool connected therewith having completed its operation upon the work, the rotation of the crank-disk 76 serves through the connecting rods 78, 79 to draw back the auxiliary feed-slide 32, or more strictly permits said slide to be moved

backward by the action of the spring 92 under the control of the rotating crank-disk. It will be further noted that in the construction shown, even after the roll has passed by the high point of the cam, the main slide will be prevented from being drawn forward by the rotation of the crank-disk 76 by the engagement of the projection 66^a on the segment-lever with the frame. Moreover, even if such projection were not present, the greater weight of the main slide, as compared with that of the auxiliary slide, in connection with the spring-pressed plunger 93 acting on the segment-lever, would serve to prevent forward movement of the main slide and insure that only rearward movement of the auxiliary slide will be produced by the rotation of the crank-disk at this time.

As the auxiliary slide is moved backward by the action of the spring 92 under the control of the crank-disk 76, and just before said slide reaches its rearmost position, the projection 91 on the hook-lever 87 is brought into engagement with the fixed cam 90, thereby turning said hook-lever about its pivot so as to withdraw the hook of said lever from the notch 88, thus disconnecting the two parts of the connecting rod and consequently disconnecting the auxiliary feed-slide from the main slide. When the parts have been thus disconnected the spring 92 acts to complete the rearward movement of the auxiliary slide and to move the same against the fixed abutment 32^a, against which abutment, as above stated, the auxiliary slide is held by said spring during the indexing operation. As the crank-disk 76 continues to rotate it will serve to move the part 78 of the connecting rod with relation to the part 79, further movement of said part 79 being prevented by the engagement of the auxiliary slide with the fixed abutment, until the parts are brought into the position shown in Fig. 9, which is the position they occupy at the time the indexing of the turret-head begins. The indexing operation then takes place, the auxiliary slide remaining stationary against the fixed abutment during such indexing operation. During the operation of indexing the crank-disk 76 is moved from the position shown in Fig. 9 to the position shown in Fig. 10. With the feed-cam 63 formed as shown in the drawings the main feed-slide will, at this time, by the action of the spring-pressed plunger 93 on the segment-lever, have been moved backward from the position shown in Fig. 9 to the position shown in Fig. 10; such backward movement of the main slide being permitted by the shape of the feed-cam 63, whereby the roll 67 has been caused to pass down to the low point of the cam, as shown in Fig. 10. By reason of such backward movement of the main slide the crank-disk 76 carried thereby, together with the part

78 of the connecting rod, are likewise carried backward to the same extent, thereby bringing the parts into the position shown in Fig. 10. It will be understood that with the parts in this position the indexing of the turret-head has been completed.

There remains to be described the reconnection of the two parts of the connecting rod and the advancing movement of the auxiliary slide by the quick-acting mechanism to bring the tool carried by the tool-spindle now connected with said slide up to the work. As will be understood, the crank-disk 76 continues to be rotated until the crank-pin 77 is moved from the position shown in Fig. 10 to the position shown in Fig. 8, that is, to the position which it occupied when said crank-disk began its rotation. Such continued rotation of the crank-disk serves to move the part 78 of the connecting rod with relation to the part 79 until the forward end of the part 78 is caused to abut against the shoulder on the part 79, when both parts are by the continued rotation of the crank-disk moved forward together, thereby imparting quick advancing movement to the auxiliary slide to bring the tool carried thereby up to the work. As the auxiliary slide is thus moved forward the projection 91 on the hook-lever 87 rides off of the cam 90, whereupon said hook-lever is rocked by the action of the spring 89 to cause its hook to again enter the notch 88 and thereby reconnect the two parts of the connecting rod and again connect the auxiliary slide to the main slide, and so that as the main slide is again advanced by the action of the next lobe of the feed-cam, the tool carried by the spindle then connected with the auxiliary slide will be fed along the work. As will be understood, the drop on the feed-cam will vary in the case of different lobes, being in some cases a long drop, as in the case of the lobe 63^a in the drawings, and being in other cases a short drop, as in the case of the lobe 63^b. As will be seen, when the drop is a short one the main slide will not, when it passes the high point of the cam, be moved as far backward by the action of the spring-pressed plunger as where the drop is a long one. In such case, therefore, the end of the part 78 of the connecting rod will not be moved as far away from the shoulder on the part 79 as is shown in Fig. 10, and consequently the end of said part 79 will, by the continued rotation of the crank-disk 76 be brought into engagement with the shoulder on the part 79 correspondingly earlier, and so that a greater extent of advancing movement will in such case be imparted to the auxiliary slide by the quick-acting crank-disk. When a screw-thread is to be cut on the work the die must be run off of the work before the quick-return mechanism

begins to operate. In such case, therefore, the proper tappet 104 is so adjusted that the clutch-member 40 will not be tripped and the shaft 45, therefore, will not be rotated until the die has cleared the work. During the running off of the die, therefore, the auxiliary slide and the main slide, which are at this time connected, are moved back together under the conjoint action of the spring 92 and the spring-plunger 93 under the control of the feed-cam, the drop of the proper lobe on said cam being formed to correspond to the pitch of the thread cut and thus to the movement of the die in running off. It may be noted that either one of the springs referred to would serve to effect such backward movement of the slide, but in the construction shown both springs coöperate in the production of this result. When the die has cleared the work the clutch member 40 is tripped, thereby starting the rotation, through the shaft 45, of both the indexing crank-disk 49 and the crank-disk 76. This serves to start the operation of the indexing mechanism and also the operation of the quick return mechanism, which latter will then act to cause the auxiliary slide to be moved with relation to the main slide until the two parts of the connecting rod have been disconnected and until the auxiliary slide brings up against its fixed abutment, the operation after the die clears the work being the same as hereinbefore described.

It may often be desirable, as in setting up the machine or otherwise, to index the turret-head by hand or to move the auxiliary feed-slide to its rearward position by hand for some other purpose, and this is made possible by the construction shown. By withdrawing the spring pressed pin 83 from engagement with the pin or projection 81 on the block 80 the auxiliary feed-slide will be thereby disconnected from the crank-disk 76, although the block 80 will remain connected therewith. Consequently the auxiliary slide will be free to be moved backward to any desired position, as for example to its extreme rearward position, as shown in Fig. 5, and so that the turret may, if desired, be then indexed by hand, and the auxiliary slide then returned to its normal position and reconnected with the block 80 and the crank-disk 76. Inasmuch as it might happen that the operator, after thus disconnecting the auxiliary slide and moving it backward, might forget to return said slide to its normal position and reconnect the same with the block 80, means are provided whereby, if this should happen, said slide will, when the crank-disk 76 is next rotated, be automatically reconnected with said block. Thus when the pin 83 is pulled out of the hole in the projection 81, the auxiliary slide moved backward, and the pin

released, the inner end of said pin will bring up against and will ride along the outer face of the part 78 of the connecting rod. When now the crank disk 76 is rotated with the parts in this position the rotation of said crank-disk will act to move the block 80 rearward until the hole in the projection 81 comes in line with the pin 83, when said pin will, under the action of its spring, be snapped into said hole and the parts be thereby automatically reconnected. It will be noted that the annular shoulder 81^a on the projection 81 will, as the block 80 is thus moved rearward, come in contact with the end of the pin 83, thereby preventing the hole in the projection 81 from passing by the pin and causing the pin to enter said hole. Preferably the spring 84 is so wound that upon the withdrawal of the pin 83 the coils of the spring will come together when said pin has been withdrawn sufficiently to clear the cut-away portion of the end of the projection 81. With this construction, as will be seen, the annular shoulder 81^a will also serve to prevent the auxiliary slide 90 from being moved forward of its connected position and will thus prevent the pin 83 from being moved on to the forward side of the projection 81.

With the construction above described, as will be seen, the quick return and advancing movements are not imparted to the heavy main feed-slide, but are instead imparted only to the auxiliary feed-slide, which is much lighter in weight, and as these quick movements are thus imparted only to this relatively light part, the speed of these movements may be materially increased with a corresponding saving of time and increase in production. Moreover by the employment of separate and individually movable tool-spindles, only one of which requires to be reciprocated with the auxiliary slide at any one time, the turret-head itself having no longitudinal movement, the total weight to be retracted and advanced by the quick-acting mechanism is limited to the weight of the auxiliary slide plus the weight of a single tool-spindle, thereby making possible a still further increase of speed.

When separate individually movable tool-spindles are employed in an indexing turret-head it is desirable that each spindle shall in turn be retracted to the same definite position in order that when the turret-head is indexed the next tool-spindle will be certain to be engaged with the actuating device. Consequently it is desirable in the present machine that the auxiliary feed-slide should always be brought back to the same definite position at each reciprocation thereof, and it is for this reason that the fixed abutment for said slide is provided. When such fixed abutment is employed it might happen that the auxiliary slide would

bring up against such abutment before the crank-disk 76 had completed its throw of 180°. If this should happen the result would be that after the auxiliary slide had brought up against its abutment the further rotation of the crank-disk would serve to impart a forward movement to the main slide. This would result in the quick movement of a heavy part, which would be objectionable. Moreover, if the main slide were thus moved forward it might serve to move the roll 67 out of engagement with the feed-cam and entirely away therefrom, and so that when said roll were again moved toward the feed-cam by the further rotation of the crank-disk, it would be brought into contact with said cam at a high speed and thus with considerable force, causing a shock and jar to the machine, which would be further objectionable. By providing means for disconnecting the auxiliary slide from the crank-disk at or before the time said auxiliary slide brings up against its abutment, said crank-disk may rotate through its further throw without imparting any movement either to the auxiliary slide or to the main slide. Moreover, by providing means for thus disconnecting the auxiliary slide from the crank-disk and thus from the main slide, said auxiliary slide is thereby released from any action of the crank-disk, and so that said auxiliary slide will thus not only be brought back to the same definite position at each reciprocation, but may be held in that position throughout the indexing operation. In other words, the provision of thus disconnecting the auxiliary slide makes possible and brings about a dwell of the auxiliary slide in its rearward position during the time the turret-head is being indexed.

It may be noted that by providing the projection 66^a on the segment-lever to abut against the frame, whereby the main slide is prevented from being pulled forward when the crank-disk 76 is rotated, the rotation of said crank-disk will serve to bring about the quick return of the auxiliary slide, even if the spring 92 should be absent or fail to operate. Thus if, as may sometimes happen, a tool should stick on the work, and so that the spring 92 was insufficient to withdraw the tool from the work, the rotation of the crank-disk would serve, by reason of the engagement of the projection 66^a with the frame, to positively withdraw the tool clear of the work, when the spring 92, is present, would serve to complete the return movement of the auxiliary slide under the control of the crank-disk.

While the machine shown and described is of that type in which the several tools are mounted in individually movable spindles, each of which is separately advanced and retracted, the underlying feature of inven-

tion, which consists in the combination, with a main slide, of an auxiliary slide, and means for giving quick return movements only to said auxiliary slide, may be employed in other types of machines.

70

It will be understood that while the machine is especially adapted for making metal screws and is commonly referred to as a screw machine, said machine is also adapted for making a great variety of other articles, and where the term "screw machine" is employed in the specification and claims such term is employed to designate the general character of the machine and without reference to the particular articles made thereby.

80

What I claim as my invention and desire to secure by Letters Patent is:

1. A screw machine having in combination a main slide, a tool carrying auxiliary slide mounted on said main slide, and means for imparting a quick return movement to said auxiliary slide.

2. A screw machine having in combination a main slide, a tool carrying auxiliary slide mounted on said main slide, means for advancing said auxiliary slide, and means for imparting a quick return movement to said auxiliary slide.

3. A screw machine having in combination a main slide, a tool carrying auxiliary slide mounted on said main slide, means for advancing both of said slides, and means for imparting a quick return movement to said auxiliary slide.

4. A screw machine having in combination a main slide, a tool carrying auxiliary slide mounted on said main slide, and means mounted upon said main slide adapted to effect a quick return movement of said auxiliary slide.

105

5. A screw machine having in combination a main slide, an auxiliary slide, means for advancing said slides, a spring acting upon said auxiliary slide tending to return the same, and means for controlling the action of said spring.

110

6. A screw machine having in combination a main slide, an auxiliary slide, means for advancing said slides, a spring acting upon said auxiliary slide tending to return the same, and means mounted upon said main slide for controlling the action of said spring.

115

7. A screw machine having in combination a main slide, an auxiliary slide, mechanism connecting said slides, and means for causing said connecting mechanism to impart movement to said auxiliary slide while the main slide remains stationary.

120

8. A screw machine having in combination a main slide, an auxiliary slide, a crank connection between said slides, and means for causing said crank connection to impart movement to said auxiliary slide while the main slide remains stationary.

125

130

9. A screw machine having in combination a main slide, an auxiliary slide, means for advancing said slides, and means for returning said auxiliary slide independent 5 of said main slide. 65
10. A screw machine having in combination a main slide, an auxiliary slide, means for advancing said slides, and means carried by said main slide adapted to effect a return 10 of said auxiliary slide independent of said main slide. 70
11. A screw machine having in combination a main slide, an auxiliary slide, a cam for advancing said slides, and means for 15 returning said auxiliary slide independent of said main slide. 75
12. A screw machine having in combination a main slide, an auxiliary slide, a cam for advancing said slides, and means carried 20 by said main slide adapted to effect a return of said auxiliary slide independent of said main slide. 80
13. A screw machine having in combination a main slide, an auxiliary slide, a turret-head, means for indexing said turret-head, means for advancing said slides, and means operating in connection with said indexing mechanism for returning said auxiliary 25 slide. 85
14. A screw machine having in combination a main slide, an auxiliary slide, a continuously moving cam for advancing said slides, and intermittently operating means for returning said auxiliary slide. 90
15. A screw machine having in combination a main slide, an auxiliary slide, a continuously moving cam for advancing said slides, and intermittently operating means, carried by said main slide for returning said 30 auxiliary slide. 95
16. A screw machine having in combination a main slide, an auxiliary slide, means for advancing said slides, a turret-head, means for indexing said turret-head, and 45 means carried by said main slide and operating in connection with said indexing mechanism for returning said auxiliary slide. 100
17. A screw machine having in combination a main slide, an auxiliary slide, means for advancing said slides, a turret-head, means for indexing said turret-head, and means carried by said main slide and operating in connection with said indexing 55 mechanism for returning said auxiliary slide. 105
18. A screw machine having in combination a main slide, an auxiliary slide, a cam for advancing said slides, a turret-head, and means for indexing said turret-head, and means operating in connection with said indexing mechanism for returning said auxiliary slide. 110
19. A screw machine having in combination a main slide, an auxiliary slide detachably connected to said main slide, and means for imparting independent movement to said auxiliary slide. 115
20. A screw machine having in combination a main slide, an auxiliary slide detachably connected to said main slide, and means for automatically disconnecting said auxiliary slide from said main slide. 120
21. A screw machine having in combination a main slide, an auxiliary slide detachably connected to said main slide, and means for automatically disconnecting said auxiliary slide from said main slide and reconnecting the same therewith. 125
22. A screw machine having in combination a main slide, an auxiliary slide detachably connected to said main slide, a spring for returning said auxiliary slide, means for controlling the operation of said spring, and means for disconnecting said auxiliary slide from said main slide. 130
23. A screw machine having in combination a main slide, an auxiliary slide detachably connected to said main slide, a spring for returning said auxiliary slide, means for controlling the operation of said spring, means for disconnecting said auxiliary slide from said main slide, and a stop for arresting the return movement of said auxiliary slide. 135
24. A screw machine having in combination a main slide, an auxiliary slide detachably connected to said main slide, a spring for returning said auxiliary slide, means carried by said main slide for controlling the operation of said spring, means for disconnecting said auxiliary slide from said main slide, and a stop for arresting the return movement of said auxiliary slide. 140
25. A screw machine having in combination a main slide, an auxiliary slide, a spring for returning said auxiliary slide, and means for controlling the operation of said spring and adapted to effect the return movement of said auxiliary slide if said spring fails to operate. 145
26. A screw machine having in combination a main slide, an auxiliary slide, quick return mechanism for returning said auxiliary slide independent of said main slide, and means for controlling the operation of said quick return mechanism. 150
27. A screw machine having in combination a main slide, an auxiliary slide, a cam for advancing said slides, means for partially returning both of said slides under the control of said cam, and quick return mechanism for completing the return movement of said auxiliary slide independent of said main slide. 155
28. A screw machine having in combination a main slide, an auxiliary slide mounted on said main slide, a tool carrier, and means 160

- whereby said tool-carrier may be connected with and disconnected from said auxiliary slide.
29. A screw machine having in combination a main slide, an auxiliary slide mounted on said main slide, a series of tool carriers and means whereby said tool carriers may be separately connected with and disconnected from said auxiliary slide.
- 10 30. A screw machine having in combination a main slide, an auxiliary slide mounted on said main slide, a turret-head provided with a series of tool-carriers, means for indexing said turret-head, and means for connecting said tool-carriers successively with said auxiliary slide.
- 20 31. A screw machine having in combination a main slide, an auxiliary slide mounted on said main slide, a tool-carrier, means whereby said tool carrier may be connected with and disconnected from said auxiliary slide, and means for imparting a return movement to said auxiliary slide independent of said main slide.
- 25 32. A screw machine having in combination a main slide, an auxiliary slide mounted on said main slide, a tool-carrier, means whereby said tool carrier may be connected with and disconnected from said auxiliary slide, and means for imparting a quick return movement to said auxiliary slide.
- 30 33. A screw machine having in combination a main slide, an auxiliary slide mounted on said main slide, a series of tool-carriers, means whereby said tool carrier may be separately connected to and disconnected from said auxiliary slide, and means for imparting a quick return movement to said auxiliary slide.
- 35 40 34. A screw machine having in combination a main slide, an auxiliary slide mounted on said main slide, a turret-head provided with a series of tool-carriers, means for indexing said turret-head, means for connecting said tool-carriers successively with said auxiliary slide, and means for imparting a quick return movement to said auxiliary slide.
- 45 50 35. A screw machine having in combination a main slide, a tool carrying auxiliary slide mounted on said main slide, means for imparting a quick return movement to said auxiliary slide, and means for causing a dwell of said auxiliary slide in its rearward position.
- 55 60 36. A screw machine having in combination a main slide, a tool carrying auxiliary slide mounted on said main slide, means for imparting a quick return movement to said auxiliary slide, means for causing a dwell of said auxiliary slide in its rearward position, a turret-head, and means for indexing said turret-head during the dwell of said auxiliary slide.
- 65 70 37. A screw machine having in combination a main slide, an auxiliary slide detachably connected to said main slide, means for imparting a quick return movement to said auxiliary slide, means for disconnecting said auxiliary slide from said main slide, and a stop for arresting the return movement of said auxiliary slide.
- 75 80 38. A screw machine having in combination a main slide, an auxiliary slide detachably connected to said main slide, means for disconnecting said auxiliary slide from said main slide, a stop for arresting the return movement of said auxiliary slide, and means for imparting a quick return movement to said auxiliary slide and holding said slide against said stop upon the completion of its return movement.
- 85 90 39. A screw machine having in combination a main slide, a tool carrying auxiliary slide mounted on said main slide, means for imparting a quick return movement to said auxiliary slide, means for causing a dwell of said auxiliary slide in its rearward position, and means for imparting a quick advancing movement to said auxiliary slide.
- 95 100 40. A screw machine having in combination a main slide, a tool carrying auxiliary slide mounted on said main slide, means for imparting a quick return movement to said auxiliary slide, means for causing a dwell of said auxiliary slide in its rearward position, a turret-head, means for indexing said turret-head during the dwell of said auxiliary slide, and means for imparting a quick advancing movement to said auxiliary slide.
- 105 41. A screw machine having in combination a main slide, a tool carrying auxiliary slide mounted on said main slide, means for advancing said slides, a turret-head, means for indexing said turret-head, and means for effecting the return movement of said auxiliary slide in advance of the indexing of said turret-head.
- 110 115 42. A screw machine having in combination a main slide, a tool carrying auxiliary slide mounted on said main slide, means for advancing said slides, a turret-head, means for indexing said turret-head, means for effecting a quick return movement of said auxiliary slide in advance of the indexing of said turret-head, and means for causing a dwell of said auxiliary slide in its rearward position at the time of indexing said turret-head.
- 120 125 43. A screw machine having in combination a main slide, a tool carrying auxiliary slide, a crank connection detachably connecting said slides, and means for operating said crank connection to impart a quick return movement to said auxiliary slide.
44. A screw machine having in combination a main slide, an auxiliary slide, a crank connection detachably connecting said slides,

means for operating said crank connection to impart a quick return movement to said auxiliary slide, and means for disconnecting said crank connection.

5 45. A screw machine having in combination a main slide, an auxiliary slide, a crank connection detachably connecting said slide, means for operating said crank connection to impart a quick return movement to said 10 auxiliary slide, means for disconnecting said crank connection, and means for re-connecting the same.

46. A screw machine having in combination a main slide, an auxiliary slide, a spring 15 acting on said auxiliary slide for imparting a quick return movement thereto, a crank connection detachably connecting said slides for controlling the action of said spring, and means for disconnecting said crank connection.

20 47. A screw machine having in combination a main slide, an auxiliary slide, a spring acting on said auxiliary slide for imparting a quick return movement thereto, a crank connection detachably connecting said slides for controlling the action of said spring, means for disconnecting said crank connection, and means for reconnecting the same.

48. A screw machine having in combination 25 a main slide, an auxiliary slide, a cam for advancing said slides, and means for imparting a quick return movement to said auxiliary slide independent of the main slide, the return movement of the main 30 slide being controlled by said cam.

49. A screw machine having in combination 35 a main slide, an auxiliary slide, a cam for advancing said slides, a spring acting on said auxiliary slide to impart a quick return movement thereto, a crank connection between said slides for controlling the action of said spring, and a second spring acting on said main slide to impart return movement thereto under the control of said cam.

50 50. A screw machine having in combination a main slide, an auxiliary slide, a cam for advancing said slide, a spring acting on said auxiliary slide to impart a quick 55 return movement thereto, a crank connection detachably connecting said slides for controlling the action of said spring, means for disconnecting said crank connection, and a second spring acting on said main

slide to impart return movement thereto under the control of said cam.

51. A screw machine having in combination a main slide, an auxiliary slide, a cam for advancing said slides, a spring acting on said auxiliary slide to impart a quick return movement thereto, a crank connection between said slides for controlling the action of said spring, and means for controlling the operation of said crank connection.

52. A screw machine having in combination a main slide, an auxiliary slide, a cam for advancing said slides, a spring acting on said auxiliary slide to impart a quick return movement thereto, a crank connection between said slides for controlling the action of said spring, means for controlling the operation of said crank connection, and a second spring acting on said main slide to impart return movement thereto under the control of said cam.

53. A screw machine having in combination a main slide, an auxiliary slide detachably connected thereto, and means for disconnecting said auxiliary slide from said main slide, whereby said auxiliary slide may 80 be moved by hand independent of the main slide.

54. A screw machine having in combination a main slide, an auxiliary slide detachably connected thereto, means for disconnecting said auxiliary slide from said main slide, and means for causing said parts to be automatically reconnected.

55. A screw machine having in combination a main slide, an auxiliary slide, a crank connection between said slides, said crank connection embodying a movable member by the movement of which said slides may be disconnected and said auxiliary slide be moved by hand independent of said main 95 slide.

56. A screw machine having in combination a main slide, an auxiliary slide, a crank connection between said slides, said crank connection embodying a movable member, 100 and means whereby the rotation of the crank will cause said parts to be automatically reconnected.
